TIMER MOUNTING

Gustave J. Lang, Longmeadow, and John F. Martin, Springfield, Mass., assignors to United American Bosch Corporation, Springfield, Mass., a corporation of New York

Application October 6, 1932, Serial No. 636,464

7 Claims. (Cl. 123—148)

This invention relates to improvements in timers and particularly to timers for controlling the ignition of explosive charges in the power chambers of internal combustion engines.

5 An object of the invention is to provide a timer comprising an interrupter or circuit breaker, a distributor, and a coil casing having an improved mounting by which the parts of the timer can be assembled and easily attached to the body of the

10 engine on which it is to be used.

Other objects and advantages of the invention are set forth in the ensuing description and the novel features are pointed out in the appended claims; and we of course reserve the right to make

15 changes in details that do not depart from the spirit of the invention or exceed the scope of the terms in which the claims are expressed.

On the drawings:

Fig. 1 is a longitudinal section showing one form of our timer;

Figs. 2 and 3 are similar views showing other forms or embodiments;

Fig. 4 is a front view of the circuit breaker of the timer.

25 The same numerals identify the same parts throughout.

Referring first to Fig. 1, we show at 1 a cover, usually of cast metal, for the gear case of an internal combustion engine. This cover or support carries the mounting for our timer which comprises a housing 2 of aluminum or any other suitable material. On the top of the housing is a casing 3 for the ignition coil, and on the outer end of the housing is a distributor casing 4.

30 Within the housing and abutting the cover 1 is a cast-iron casing 5 having at one end a bearing 6 which projects into the central opening 7 in the cover 1 to enable the timer shaft 8 to be connected to the gear shaft and be driven thereby. The

40 casing 5 terminates short of the front end of the housing 2; and within the front end of said housing is another bearing 9 for the shaft 8, this bearing being supported by a transverse web or the like 10. The shaft 8 projects into the distributor

45 casing 4 and on said shaft in the casing 4 is the distributor rotor 11 of insulation to which is attached a spring brush 12. This brush makes contact with a terminal 13 in the casing 4 connected by a conductor 14 to the high tension terminal 15

50 of the secondary coil in the casing 3. The rotor 11 also carries a brush 16 affixed, with the brush 12, to the rotor by rivet 17 and this brush comes into circuit closing position successively with the terminals 18 of the distributor, which are joined

55 by conductors, not shown, inserted at their ends

into openings 19, to the spark plugs of the engine.

The shaft 8 carries within the housing 2 adjacent the bearing 9 a cam 20 which extends into the casing 5 and has secured to its inner end within said casing, a plate 21. Within this casing, is another plate 22 rigid with the shaft 8 and 60 23 are governor weights joined by pivot pins 24 to the plate 21 and carrying studs 25 which project into suitably shaped openings 26 in the plate 22.

At the front or open end of the casing 5 is a flange 65 27 providing a shoulder to engage a closure plate 28 perforated in the middle for the shaft 8 and cam 20, and on this plate is an insulating stud 29 secured by rivet 30; and on the stud 29 is a spring 31 connected by a spiral conductor 32 to the primary coil in the casing 3, the other terminals of the primary and secondary coils being grounded.

70 Affixed to the plate 28 also is a pivot stud 33 carrying the hub of a breaker lever 34 which operates a movable contact point to engage and disengage 75 a fixed contact point to open and close the primary circuit when the lever 34 is operated by the cam 20. The spring 31 will be leaf-shaped and it will extend to the end of the lever 34 carrying the movable contact; serving both to connect said 80 contact to the primary coil and to hold the lever in circuit breaking position. These details of construction are not part of this invention and are well-known in this art. They are shown, however, in Fig. 4 which illustrates the timer 85 parts in front elevation. As this figure illustrates, we may use two rivets 30 for the stud 29, and the pivot of the breaker lever may be located in any suitable relative position with respect to this insulating stud; being either diametrically opposite the same as indicated in Fig. 1 or closer as indicated in Fig. 4.

75 The web 10 may have a sight opening 35 therein to permit inspection of the breaker contact points and the interrupter plate 28 may be held in place 95 by a spring ring 36 having an inside groove in the casing 5 to hold the plate against the flange 27. The casing 5 abuts a shoulder 37 in the housing 2 and at its opposite end it fits into a recess in the cover 1, the bottom of this recess being shown at 100 38 and the side 39 enveloping the casing 5. At the top 40 the housing 2 is flat to enable the casing 3 to rest thereon and it has an opening 41 through which the conductor 32 enters the housing. The casing 5 may have an oil drain 42 which 105 enters through a recess in the lower part of the housing 2 in the cover 1, and at 43 and 44 are oil retaining rings surrounding the bearing 6 and shaft 8.

With this construction it is obvious that the 110

parts can be very easily assembled. The casing 5 receives the shaft 8 and governor through the open front and then the interrupter plate 28 is inserted into the casing 5 and the entire casing 5 is then disposed in the housing 2. Next the distributor casing 4 and the coil casing 3 are attached and all the connections are readily made. The housing is secured to the cover 1 by means of screws or bolts engaging a suitable projection, 10 not shown, on its periphery near the end which enters the recess in the cover 1.

In the form shown in Fig. 2, the casing 5 is dispensed with and the housing 2 carries the bearing 6 for the shaft. Surrounding said bearing is a 15 projection 45 which fits into the recess in the cover 1. At the front of the housing 2 the bearing 9 is carried by a plate 10a which fits against a shoulder 37a. The housing also contains another 20 inside shoulder 27a against which the interrupter plate 28 abuts.

In the form shown in Fig. 3, the construction is similar to what is illustrated in Fig. 2 except that the cover 1 and housing 2a are cast or otherwise formed in one piece so that the bearing 6 is integral with the cover and the housing 2a projects from the cover and receives at its outer end the plate 10a as before. In both forms of the invention shown in Figs. 2 and 3, the shaft 8 with the governor and cam thereon is inserted through 25 the outer end of the housing until the inner end of the shaft engages the bearing 6. Then the plate 28 is put in place, the plate 10a is inserted 30 and the casings 3 and 4 are added.

The above mounting supports the parts of the 35 timer in a very practical manner and effectively encloses and seals the inside moving parts. It is strong and durable in construction and can be produced at little cost and securely protects the timer against dust and the risk of impairment 40 and damage from other causes.

Having described the invention, what is claimed is:

1. A timer mounting comprising a supporting cover, a housing to be affixed to said cover, the 45 housing having a flat top, a coil casing resting on said top, a distributor case secured to the front of the housing, a casing within the housing, said casing having a bearing at one end, a shaft in the bearing, a plate secured in the other end of the 50 casing within the housing, and a bearing carried within the housing adjacent the front thereof for said shaft.

2. A mounting for a timer comprising a gear cover, a housing attached thereto and supported

55

thereby, said housing having a bearing and the cover having an opening to receive said bearing, the cover also having a seat surrounding said opening, and the adjacent end of the housing having a projection engaging said seat, a coil casing on the top of the housing, a distributor casing carried by the front of the housing and a bearing plate detachably mounted in the front of the housing.

80

3. A mounting for a timer comprising a gear case cover, a housing integral therewith and projecting from the outside thereof, said cover having a central bearing, a detachable bearing plate within the housing near the outer end thereof to enable a shaft to be supported therein and in the first-named bearing, a coil casing in the top of the housing and a distributor casing secured to and enclosing the front end of the housing.

85

4. A timer mounting comprising a housing, a distributor casing carried thereby, a shaft in the 90 housing, a rotor on said shaft, a circuit breaker plate in the housing surrounding the shaft, and a bearing for the shaft in the housing between the rotor and said plate.

95

5. A timer comprising a support, a housing 100 carried by the support and projecting therefrom, the timer having a central bearing at the support, a bearing plate within the housing near the outer end thereof, a shaft in said bearings, a distributor casing at the outer end of the housing 105 and a rotor in said casing mounted on said shaft.

100

6. A mounting for a timer comprising a support, a housing on the support, said timer having a central bearing at the support, a plate within the housing adjacent the outer end thereof and 110 carrying a second bearing, a shaft in said bearings, an interrupter plate between said bearings, a coil on the housing and a conductor connected to the coil and entering said housing at a point adjacent said interrupter plate.

115

7. A mounting for a timer comprising a support, a housing on the support, said timer having a central bearing at the support, a plate within the housing adjacent the outer end thereof and carrying a second bearing, a shaft in said 120 bearings, an interrupter plate between said bearings, a coil on the housing, a conductor connected to the coil and entering said housing at a point adjacent said interrupter plate, a distributor casing on the outer end of the housing and a rotor 125 in said casing carried by said shaft.
